 ATTORNEY.

UNITED STATES PATENT OFFICE.

CHARLES EDWARD HAVILAND, OF LIMOGES, FRANCE.

DESIGN FOR A SLOP-JAR.

SPECIFICATION forming part of Design No. 24,740, dated October 8, 1895.

Application filed July 26, 1895. Serial No. 557,248. Term of patent 7 years.

To all whom it may concern:

Be it known that I, CHARLES EDWARD HAVILAND, a citizen of the United States, residing at the city of Limoges, in the Republic of France, have invented and produced a new and original Design for a Slop-Jar and other Articles, of which the following is a specification, reference being had to the accompanying drawings, forming part thereof, in which—
10 Figure 1 is a side elevation of a slop-jar bearing my design. Fig. 2 is a vertical section through a portion of same; and Fig. 3 is a top view, partly in section, on the dotted line 3 3 of Fig. 1, and indicates by the dotted line 2 2 the section on which Fig. 2 is taken.
15

The leading features of my design consist, first, in the new and original shape and configuration of the body of the jar, and, second, in the new and original shape and configuration of the body of said jar and its cover, as shown in the drawings forming a part of this application.

In the drawings, A designates the body of the jar and B the cover therefor.

25 The cover B has a concave central portion, and thence curves upward on graceful lines to the upper outer rolled and beaded edge of said cover, along which edge are the scallops

C D, the scallops D being smaller than and composing the larger scallops or sections C. 30 Upon the central part of the depressed top of the cover B is an ornamental handle E, which traverses the usual inlet-opening F in said cover.

The body A of the jar has concaved sides 35 composed of the scalloped sections G H, of the ornate form and configuration shown, the whole forming a body of ornamental character and outline. The lower edge of the body A bears the continuous beading I and scalloped sections J, the latter harmonizing with the sections G of the body A and being subdivided into the smaller scallops K. Upon opposite sides of the body A may be provided handles L. 40 45

What I claim is—

The design for a slop jar and its cover, substantially as shown and described.

Signed at the city of Limoges, in the Republic of France, this 8th day of July, A. D. 50 1895.

CHARLES EDWARD HAVILAND.
